UNITED STATES PATENT OFFICE.

JOHN D. BOUGHNER, OF YORBA LINDA, CALIFORNIA.

DRILL-ROD CONNECTION.

1,273,724.

Specification of Letters Patent. Patented July 23, 1918.

Application filed October 29, 1917. Serial No. 199,182.

To all whom it may concern:

Be it known that I, JOHN D. BOUGHNER, a citizen of the United States of America, residing at Yorba Linda, county of Orange,

5 State of California, have invented a certain new and useful Drill-Rod Connection; and I do hereby declare the following to be a full, clear, and exact description of the invention, such as will enable others skilled in the art

10 to which it appertains to make and use the same.

This invention relates to improvements in drill rod connection, more particularly to improvements in the construction which is

15 disclosed in my Patent No. 1,075,896, dated October 14, 1913.

One object of the invention is to provide a novel and improved form of drill rod connection which can be easily and quickly connected to or disconnected from the drill rod.

Another object of the invention is to provide a novel and improved drill rod connection which is constructed and applied to the drill rod so as to overcome practical difficulties heretofore due to crystallization and breakage of some part in the drill rod connection.

Further objects of the invention are to provide a novel and improved construction 30 for the drill rod connection which is comparatively simple in design; durable, convenient and effective in use; practical and commercial; and which facilitates manipulation and operation, and saves time and effects better working and results in practice.

With the above and other apparent objects in view, the invention may be said to consist in the provision of the novel and advantageous features and in the novel and improved 40 construction, arrangement, and combination of parts as will be evident from the following description of the preferred embodiment of the invention, taken in connection with the accompanying drawings in which—

45 Figure 1 is a broken view of the rod and drill to which the invention is applied; Fig. 2 is an enlarged broken view of the same; Fig. 3 is a longitudinal sectional view taken on the line 3—3 of Fig. 2; Fig. 4 is an enlarged cross-sectional view taken on the line 4—4 of Fig. 3; Fig. 5 is a broken longitudinal sectional view taken on the line 5—5 of Fig. 4; Fig. 6 is a broken elevational view showing a modified form of connection of 55 the cable to the crowfoot support; Fig. 7 is a plan view taken on the line 7—7 of Fig. 6;

and Fig. 8 is a broken sectional view showing sections of metallic sheathing on the cable.

The drill bit 10 may be of the usual or any 60 suitable form, and it is preferably provided with the passageways 11 and 12 for water to facilitate drilling operations. The hollow drill rod is preferably made up of sections 13 connected by the unions 14.

The construction of the improved drill rod connection—which is applied to the drilling apparatus to permit of easy and quick recovery of the apparatus when it is broken—

70 will now be described.

A column of four or five of the sections 13 connected by the unions 14 has the threaded upper and lower ends thereof screwed into one end of the hollow fittings 15 and 15' which latter have the other end thereof preferably formed tapered and provided with the annular shoulder 16. On the tapered end of each of the fittings 15 and 15' are screwed one end of the cylinders 17 and 17'. The fittings 15 and 15' and the cylinders 17 and 17' 80 are thicker and therefore stronger than the sections 13 so that if the sections 13 are broken in use said fittings and cylinders will remain unbroken. The drill bit 10 is suitably connected to the cylinder 17 which 85 is lowest in position.

A cable 18 has its upper end attached to the crowfoot 19 or other suitable support which rests on the shoulder 16 of the upper fitting 15'; and said cable 18 extends downwardly and is provided on its lower end with a head 20 which latter is disposed in the lower cylinder 17 and adapted when moved upwardly to engage the shoulder 16 of the lower fitting 15. The cable 18 is preferably 95 protected by sections 21 of metal sheathing so that said cable is not likely to be cut or damaged when a break occurs in the hollow drill rod.

As shown in Figs. 3 and 5 the cable 18 at 100 its lower and upper ends has its strands spread apart in the tapered bore of the boxes or sockets 22 and 22' and secured by babbitt or the like applied thereto. The head 20 and the crowfoot 19 are preferably provided with stems 23 and 23' which are screwed into the sockets 22 and 22'.

As shown in Figs. 6 and 7 the crowfoot 24 may be split and provided with suitable clamping plates 25 which can be connected 110 together by the bolts 26 to clamp the cable 18 therebetween.

From the foregoing the construction and advantages of the improved drill rod connection will be understood by those skilled in the art. It will be evident that though 5 the drill rod connection has been described as applied to the lower part of the drilling apparatus, the same construction can be duplicated according to the number of joined sections 13 of the drill rod as may be 10 required by the depth of the drilled hole 27 in the ground 28. When a column of the joined sections 13 is to be added to the construction shown in the drawings, it will be understood that the lower end of said column 15 is screwed into a fitting 15 on the upper end of the cylinder 17', and the head 20 on the lower end of the next section of cable 18 will be disposed in the cylinder 17'. When 20 a break occurs in any of the sections 13 of the drill rod and the latter is raised by suitable means, the heads 20 will engage the shoulders of the fittings 15 and the sections 13 of the drilling apparatus are so tied together that they can all be raised at the 25 same time.

I claim:

1. The combination with a hollow drill rod, of hollow fittings connected to the upper and lower ends of said hollow drill 30 rod and formed with shoulders, cylinders connected to said fittings, said cylinders being thicker and therefore stronger than said hollow drill rod, a support resting on the shoulder of the upper fitting, and a cable

connected to said support and provided with a head disposed in the lower cylinder, said head being normally spaced from the lower fitting and adapted to engage the shoulder of said lower fitting substantially as and for the purpose set forth. 35

2. The combination with a substantially vertical hollow drill rod, of a fitting having one end thereof connected to the upper end of said hollow drill rod, and a fitting having one end thereof connected to the lower end of said hollow drill rod, said fittings being hollow and each having the other end thereof formed tapered and provided with a shoulder, cylinders connected to said fittings, said cylinders being thicker and therefore stronger than said hollow drill rod, a crowfoot support resting on the shoulder of the first mentioned fitting, a cable having its upper end attached to said support, and a head attached to the lower end of said cable and disposed in the lower cylinder, said head being normally spaced from the second mentioned fitting and adapted to engage the shoulder of the second mentioned fitting substantially as and for the 40 purpose set forth. 45

In testimony whereof I have signed my name to this specification at Yorba Linda, county of Orange, State of California, this 13th day of October, A. D. 1917.

JOHN D. BOUGHNER.
